Primary Examiner — Daniel Bui(74) *Attorney, Agent, or Firm* — Baker & Hostetler LLP(57) **CLAIM**

The ornamental design for an electrical connector, as shown and described.

DESCRIPTION

FIG. 1 is a top, right, front perspective view of a connector housing for an electrical connector showing my new design; FIG. 2 is another top, right, front perspective view thereof; FIG. 3 is a top, left, rear perspective view thereof; FIG. 4 is a bottom, left, rear perspective view thereof; FIG. 5 is a bottom, right, front perspective view thereof; FIG. 6 is a front elevation view thereof; FIG. 7 is a rear elevation view thereof; FIG. 8 is a top plan view thereof; FIG. 9 is a bottom plan view thereof; FIG. 10 is a left side elevation view thereof; and, FIG. 11 is a right side elevation view thereof.

In a preferred embodiment, the nature of this product is an electrical component that can take the form of an electrical connector, and a connector housing therefor.
